HYDRAULIC TORQUE TRANSMITTING
DEVICE

Adiel Y. Dodge, Rockford, Ill.

Application October 7, 1938, Serial No. 233,843

5 Claims. (CL. 60—54)

This invention relates to hydraulic torque transmitting devices such as fluid flywheels and hydraulic torque converters.

One of the objects of the invention is to provide a hydraulic torque transmitting device in which the parts are so arranged and proportioned as to form a fluid circuit through which the fluid will flow smoothly with maximum torque transmitting efficiency.

Another object of the invention is to provide a hydraulic torque transmitting device in which turbulence is confined to the impeller or driving member.

Heretofore it has been the common practice of designers of hydraulic machines such as centrifugal pump-turbines, fluid flywheels and torque converters to follow the practice of maintaining practically a constant rate of so called radial flow f . This means that the flow areas are nearly constant save for the change in area brought about by the change of vane angle i. e., the area of the inlet times the sine of the inlet angle of the vanes equals the outlet area times the sine of the outlet angle of the vanes. The flow velocity relative to the vane (i. e. V) has been varied only slightly except by the function of the vane angle. When varied other than by the vane angle, it has been slight and in the direction of making impellers converging and turbines or rotors diverging; i. e. f increasing in impellers and decreasing in turbines.

I have found that much smoother fluid flow with less turbulence and less heating of the fluid can be obtained by providing diverging flow area in the impeller and converging flow area, through the rotor and, in the case of a torque converter, through the stator. This produces a decreasing f in the impeller and an increasing f through the remainder of the hydraulic circuit.

The above and other objects, advantages and novel features of the invention will be more fully apparent from the following description when read in connection with the accompanying drawing, in which:

45 Figure 1 shows a diagrammatic axial section of a torque converter;

Figure 2 shows a fragmentary cross section on the line 2—2 of Figure 1;

50 Figure 3 shows a flow area diagram pertaining to the torque converter of Figure 1;

Figure 4 shows a diagrammatic axial section of a fluid flywheel;

Figure 5 shows a fragmentary cross section at line 5—5 of Figure 4; and

55 Figure 6 shows a flow area diagram pertaining to the fluid flywheel of Figure 4.

Referring more particularly to Figure 1, there is shown a hydraulic torque converter comprising an impeller casing 10 connected to a suitable driving shaft 11 such as the crankshaft of an in-

ternal combustion engine and carrying a fixed set of vanes 12 and a set of vanes 14 pivoted adjacent the outlet ends of vanes 12. The vanes 12 carry a core member 13 defining with the casing 10 a passage through the vanes. A rotor is rotatably mounted in the casing 10 and carries spaced sets of vanes 16 and 18 arranged respectively adjacent the impeller outlet and inlet and connected by a core member 20. Between the vanes 16 and 18 there is arranged a set of stator vanes 22 mounted on a combined one way clutch and bearing 24 which will permit forward rotation but prevent reverse rotation thereof and which may be of the type more particularly described and claimed in my Patent No. 2,113,722.

The torque converter turbine rotor drives a driven shaft 26 which is formed at its end as a gear carrier carrying a set of planet pinions 28 meshing with an annular gear 30 on the rotor and with a sun gear 32 on an extension 33 of the driving shaft. This forms a two path driving connection with the shaft 26 driven jointly by sun gear 32 and by gear 30 through the torque converter, this type of connection being more particularly described and claimed in my co-pending application Serial No. 723,083 filed April 30, 1934.

In operation fluid flows radially outward through the impeller and radially inward through the two sets of rotor vanes and the stator, driving the rotor by reaction against the vanes. As the rotor speed approaches that of the impeller, fluid leaves the vanes 16 with a forward component, striking the backs of the stator vanes and driving the stator forward freely on the one-way clutch 24. At this time the action is like that of a fluid flywheel.

I have found by actual tests that better results are obtained when the flow area in the impeller is greater than the flow area in the other elements. This causes a variation in radial flow or f so that f in the impeller is less than in the other elements. The flow area referred to is the net flow area at any given point or station and to make this clear the following definitions are referred to:

Major gross flow area equals the whole passage area with vanes removed.

Minor gross flow area equals major gross flow area times the sine of the vane angle.

Net flow area A equals minor gross flow area minus area of vanes normal to flow.

Mean flow area of any element is the average net flow area at all points in that element.

If Q equals the quantity of liquid circulating

$$\text{velocity flow} = V = \frac{Q}{A}$$

and

$$\text{radial flow} = f = V \sin X$$

It is apparent that the net area A can be con-

trolled by the breadth of the passage and by the gap between vanes and the gap between vanes can be controlled by the vane thickness. In the diagrams shown Fig. 1 to 6 inclusive no attempt has been made to show the vane thickness nor the vane shape or angle, but the net results of flow area A have been diagrammed. Figure 3 shows diagrammatically the rate of change of area A in one of my hydraulic torque converters. The areas through the several sets of vanes are indicated by the same reference numerals as the vanes and the flow is in the direction of the arrows.

It will be noted from Figure 3 that the entrance of the impeller is smaller than the exit and much smaller than the mean area so that the impeller is diverging in area for the major portion of its length and is slightly choked down at its exit. The other elements as rotor vanes 16 and stator 22 are converging to simulate a nozzle action and the rotor vanes 18 are shown of uniform area throughout although they may either converge or diverge slightly. By actual test of a device constructed with these proportions it was found that improved results were obtained and that pulsation was eliminated.

These improved results are believed to be due to elimination of turbulence in the rotor and stator and to maintenance of pressure in the rotor and stator to eliminate cavitation. Since the rotor and stator are converging the fluid stream therein is accelerating and it is well known that turbulence rarely occurs in an accelerating confined stream. It is believed that pulsation is caused by cavitation first in one element and then in another and by eliminating cavitation in the rotor and the stator the pulsation is eliminated.

The impeller is the only element in which the area is not converging so that if turbulence occurs it must occur in the impeller. However, I have found that all turbulence in the impeller is not harmful and that it creates less loss in the impeller than in any of the other elements.

The impeller acts in the manner of a centrifugal pump and creates pressure in the liquid by the action of centrifugal force which is a result of acceleration toward the center of rotation. Any turbulence in the impeller is made up of components a , $\pm b$, c' , and c^2 as indicated on Figures 1 and 2, component a being counter to the flow v , $+b$ being in the direction of tangential movement of the impeller and $-b$ being counter thereto, and c' and c^2 being at right angles to the tangential movement.

Any particles traveling in the direction of a or $+b$ will have increased acceleration toward the center and therefore increased centrifugal force resulting in an increased pressure head acting on such particles. This leaves $-b$ and c to be considered. In all probability $-b$ does not exist to any noticeable extent since the greater velocity always exists along the pressure side of impeller vanes, but should it exist it can travel only a distance less than the gap between vanes before it must convert itself into the a or c components or ceases to be turbulence by joining the flow v . Turbulence in the direction of c' or c^2 can only travel a distance less than the breadth between 70 vanes before it must convert itself into a or $+b$. Therefore it is of no great consequence. We have now considered components along the six major axes namely a , $+b$, $-b$, c' , c^2 and v , it is apparent that digression in a direction lying between any 75 of these axes can be broken up into components

along these axes, hence we have considered all effects.

In conclusion turbulence either increases centrifugal force or centrifugal force decreases turbulence or both. Since one of the main functions of the impeller is to produce pressure head by centrifugal force, anything which helps that end is not a loss. Therefore turbulence in the impeller, if it occurs, is not necessarily harmful and certainly does not create the same disadvantages as it occurred in the rotor or stator.

Decreased area in the rotor increases the resistance against the impeller thereby allowing more pressure head to build up in the impeller and improving working conditions for the impeller which functions as a centrifugal pump. This causes increased velocity through the other elements which is desirable save for the increased friction, but the increased discharge velocity from the rotor into the impeller introduces a problem. According to the Bernoulli theorem velocity can be converted into pressure and vice versa. But practice shows that it is much more difficult to convert velocity into pressure than to convert pressure into velocity efficiently. The chief reason for the difficulty is because of losses due to turbulence. I have shown that turbulence is controlled to a large extent in my impeller, or that the turbulence is arrested or made use of. If the turbulence is minimized the Bernoulli effect is more complete.

Thus the present invention provides a rotor of increasing velocity with high discharge velocity, forming a small but powerful rotor having a good tangential discharge component at high speed and a stator which is more effective throughout the entire range and particularly at high speed. The impeller has a lower velocity discharge than intake and still lower mean velocity and acts as a dynamic draft tube as well as a centrifugal pump. These features make possible a wider range torque converter and one which is capable of torque multiplication at higher speeds.

Since the pressure head in the impeller must balance the counter head in the rotor and stator as well as overcome friction losses in the circuit a certain amount of slip between the rotor and stator is necessary. I have found that a torque converter can be designed for high efficiency at all torque ratios which will give a 6% slip at full engine torque and 3000 R. P. M. Due to the gear arrangement this produces less slip, of the magnitude of 4.6% between the input and output shafts assuming the mean impeller discharge and the rotor intake periphery is 3 feet and the mean impeller intake and rotor outlet periphery is 1.3 feet and 6% slip; then

Impeller speed	= 50 R. P. S.	60
Rotor speed	= 47 R. P. S.	
U_1 impeller	= $50 \times 1.3 = 65$ ft./sec.	
U_0 impeller	= $50 \times 3 = 150$ ft./sec.	
U_1 rotor	= $47 \times 3 = 141$ ft./sec.	
U_0 rotor	= $47 \times 1.3 = 61$ ft./sec.	

where U_1 is the inlet tangential velocity and U_0 is the outlet tangential velocity.

$$H \text{ impeller} = \frac{150^2}{2g} - \frac{65^2}{2g} - \frac{f_i^2}{2g} = 282 - \frac{f_i^2}{2g}$$

$$\text{counter H rotor} = \frac{141^2}{2g} - \frac{61^2}{2g} - \frac{f_r^2}{2g} = 249 + \frac{f_r^2}{2g}$$

Where f_i is the average radial flow through the impeller and f_r is the average radial flow through the rotor.

Since these heads must balance

$$282 - \frac{f_i^2}{2g} = 249 + \frac{f_r^2}{2g}$$

$$5 \quad \frac{f_i^2}{2g} + \frac{f_r^2}{2g} = 33$$

This equation is satisfied if

$$10 \quad f_i = 20 \text{ and } f_r = 42 \text{ or}$$

$$f_i = 15 \text{ and } f_r = 44$$

This indicates an allowable ratio of

$$\frac{f_r}{f_i}$$

15 for 6% slip of

$$\frac{44}{15} = 2.93$$

When considering the returned head to the impeller a velocity or flow area ratio of about 3.1 to 1 is permissible indicating that the area in the rotor and stator may be slightly less than one third that in the impeller.

With the above as a basis I have found the following flow area ratios for hydraulic torque converters produce highly efficient results:

Ratio of average impeller area to average rotor and stator area = 2.1 to 3.1.

Maximum impeller area to minimum rotor or stator area = 4.1 to 6.1.

Maximum impeller area to minimum impeller area = 2.5 to 3.5.

Impeller outlet area to impeller inlet area = 1.75 to 2.5.

35 One of the principal advantages of a torque converter designed according to the present invention is that it operates efficiently both as a torque multiplying device and as a fluid clutch in which there is no torque increase. This latter condition occurs when the stator overruns the clutch 24 and turns with the rotor, the device at this time transmitting torque in the manner of a fluid clutch and maintaining a high efficiency throughout the operating range. Thus I have 40 provided a combined torque converter and fluid clutch in a single unit which is very desirable for many transmission uses.

Figures 4 to 6 illustrate a fluid flywheel or hydraulic clutch coupling embodying the invention, parts therein corresponding to like parts in Figures 1 to 3 being indicated by the same reference numerals plus 100. In this construction the impeller is very similar to that of the torque converter but the rotor has only a single set of vanes 55 116 and is carried by the driven shaft 126, there being no stator. Turbulence effects in the impeller are identical with those in the torque converter and are indicated by similarly marked arrows.

60 Figure 6 shows the diagram of the change of areas taking place from the impeller entrance on through the rotor and back to the impeller entrance, the direction of flow being indicated by the arrows. In the case of fluid flywheel nothing can be done to change the characteristic efficiency curve but the specific efficiency can be altered. I have improved the capacity for a given size and eliminated pulsation by my low velocity diverging impeller and converging rotor.

70 Due to the fact that no torque multiplication is to be had certain of the benefits derived in my torque converter cannot be secured in my fluid flywheel. Due to this plus the fact that it is unnecessary to use two path gears with a fluid 75 flywheel the slip speed should be held down to

3 or 4% between the impeller and the rotor, hence less head difference is available.

I have found by test that the following area ratios work well in a fluid flywheel:

Average impeller flow area divided by average 5 rotor flow area = 1.2:1 to 1.5:1.

Average impeller area divided by the minimum rotor area = 1.5:1 to 2:1.

Maximum impeller area divided by minimum 10 rotor area = 1.7:1 to 2.5:1.

Maximum impeller area divided by area of impeller entrance = 1.5:1 to 2.25:1.

This application is a continuation in part of my copending applications Serial Nos. 52,530 filed December 2, 1935, since issued as Patent No. 15 2,200,596, 57,520 filed January 4, 1936, since issued as Patent No. 2,190,830, and 95,117 filed August 10, 1936.

It will be understood that the invention might be applied to torque transmitting devices having 20 different numbers or a different arrangement of elements and that the scope of the invention is not to be limited to the exact forms shown nor otherwise than by the terms of the appended claims.

25 What is claimed is:

1. A hydraulic torque converter comprising a vaned impeller, a vaned rotor having two spaced sets of vanes one adjacent the impeller outlet and the other adjacent the impeller inlet, and a vaned 30 stator between the spaced sets of rotor vanes, the impeller increasing in flow area from its inlet toward its outlet and having a larger mean flow area than any of the other elements, the first named set of rotor vanes decreasing in flow area 35 from the inlet to the outlet and having a smaller mean flow area than the impeller, the stator decreasing in flow area from its inlet to its outlet and having a smaller mean flow area than the first set of rotor vanes, and the second set of 40 rotor vanes having an inlet flow area at least as large as their outlet flow area and a mean flow area no larger than that of the stator.

2. A hydraulic torque converter comprising a vaned impeller, a vaned rotor having two spaced 45 sets of vanes one adjacent the impeller outlet and the other adjacent the impeller inlet, and a vaned 50 stator between the spaced sets of rotor vanes, the impeller increasing in flow area from its inlet toward its outlet and having a larger 55 mean flow area than any of the other elements, the first named set of rotor vanes decreasing in flow area from the inlet to the outlet and having a smaller mean flow area than the impeller, the stator decreasing in flow area from its inlet to its outlet and having a smaller mean flow area than the first set of rotor vanes, and the second set of 60 rotor vanes having a uniform flow area from inlet to outlet and a mean flow area no larger than that of the stator.

3. A hydraulic torque converter comprising a vaned impeller, a vaned rotor having two spaced sets of vanes one adjacent the impeller outlet and the other adjacent the impeller inlet, and a vaned 65 stator between the spaced sets of rotor vanes, the impeller increasing in flow area from its inlet toward its outlet and having a larger mean flow area than any of the other elements, the first named set of rotor vanes decreasing in flow area 70 from the inlet to the outlet and having a smaller mean flow area than the impeller, the stator decreasing in flow area from its inlet to its outlet and having a smaller mean flow area than the first set of rotor vanes, and the second set of 75 rotor vanes decreasing in flow area from their inlet to

their outlet and having a mean flow area smaller than that of the stator.

4. A hydraulic torque transmitting device comprising a vaned impeller and a vaned rotor arranged adjacent the impeller outlet to receive fluid therefrom said impeller and rotor being arranged in a closed fluid circuit, the net flow area of the impeller increasing from its inlet to a point adjacent its outlet and then decreasing slightly to form an outlet of larger area than the inlet, and the rotor having an inlet adjacent the impeller outlet of at least as great an area as the impeller outlet and decreasing to its outlet the impeller inlet receiving liquid from an element having an outlet smaller than the impeller inlet.

5. A hydraulic torque converter comprising a vaned impeller, a vaned rotor having two spaced sets of vanes one adjacent the impeller outlet

and the other adjacent the impeller inlet, and a vaned stator between the spaced sets of rotor vanes, the impeller increasing in flow area from its inlet to a point adjacent its outlet and then decreasing slightly to provide an outlet larger than its inlet and having a larger mean flow area than any of the other elements, the first named set of rotor vanes decreasing in flow area from the inlet to the outlet and having a smaller mean flow area than the impeller, the stator decreasing in flow area from its inlet to its outlet and having a smaller mean flow area than the first set of rotor vanes, and the second set of rotor vanes having an inlet flow area at least as large as their outlet flow area and a mean flow area no larger than that of the stator.
